UNITED STATES PATENT OFFICE

115,913

DESIGN FOR A TABLE DECORATION OR ARTICLE OF SIMILAR NATURE

Donald Oliver Crandall, Minneapolis, Minn., assignor of one-half to Cooperative Crafts, Inc., Minneapolis, Minn., a corporation of Minnesota, and one-half to Eleanor N. Poehler, Minneapolis, Minn., doing business under name of The Guild

Application May 22, 1939, Serial No. 85,134

Term of patent 7 years

To all whom it may concern:

Be it known that I, Donald Oliver Crandall, a citizen of the United States and residing in the city of Minneapolis, county of Hennepin, and State of Minnesota, have invented a new, original, and ornamental Design for a Table Decoration or Article of Similar Nature, of which the following is a specification, reference being had to the accompanying drawing, forming a part thereof, wherein,

Fig. 1 is a perspective view illustrating a table decoration or article of similar nature showing my new design; and

Fig. 2 is a plan view of the same.

I claim:

The ornamental design for a table decoration or article of similar nature, substantially as shown.

DONALD OLIVER CRANDALL.
